UNITED STATES PATENT OFFICE.

EDWARD A. ROCKWELL, OF FLUSHING, NEW YORK, ASSIGNOR TO E. A. ROCKWELL COMPANY, INC., OF NEW YORK, N. Y., A CORPORATION OF NEW YORK.

VACUUM LIQUID-SUPPLY SYSTEM.

1,420,753.

Specification of Letters Patent. Patented June 27, 1922.

Application filed June 5, 1920. Serial No. 386,904.

To all whom it may concern:

Be it known that I, EDWARD A. ROCKWELL, a citizen of the United States, residing at Flushing, in the county of Queens and State of New York, have invented a certain new and useful Improvement in Vacuum Liquid-Supply Systems, of which the following is a specification.

My invention relates particularly to an apparatus designed for supplying liquids of various kinds, but it has reference especially to an apparatus designed for feeding liquid fuels to internal combustion engines, as for example, automobile or aeroplane engines.

The object of my invention is to provide an effective apparatus for feeding liquids of various kinds for various purposes, but especially for feeding liquid fuels to internal combustion engines. Another object is to provide an apparatus of this character which is adapted to lift liquids to any desired height. Still another object is to provide such an apparatus which is inexpensive to manufacture.

Further objects of my invention will appear from the detailed description thereof contained hereinafter.

While my invention is capable of embodiment in many different forms, for the purpose of illustration I have shown only certain forms of my invention in the accompanying drawings, in which;

Fig. 1 is a diagrammatic representation of an apparatus made in accordance with my invention,

Fig. 2 is a diagrammatic representation of a modified form of my invention, and

Fig. 3 is a section on large scale of an auxiliary supply tank used with my invention.

In the drawings, referring to Fig. 1, I have shown a main supply tank 1 for containing gasoline, or any other desired liquid fuel, and which may be located at any desired point. The main supply tank 1 is provided with a removable filling cap 2 having a vent opening 3 therein. There is a fuel supply pipe 4 leading from the lower portion of the tank to a charging chamber 5 which may be slightly below or at the same level with the main supply tank 1. In the charging chamber 5, there is a float 6 carrying a valve 7 adapted to stop the flow of fuel in the pipe 4 when the liquid

level in the chamber 5 has risen to a certain height, said valve 7 being carried on a rod 8 extending through said float, and having a lower extension 9 guided in an outlet passageway 10 normally closed by a gravity closing hinged flap valve 11. Connected to the float chamber 5, there is a pressure equalizing pipe 12. Passing through said float chamber 5, there is a vent pipe 13 to vent a measuring chamber 14 located below the float chamber 5, and into which the passageway 10 discharges. Leading from the bottom of the measuring chamber 14, there is a fuel feeding pipe 15 having a restricted inlet opening 15^a which is made of comparatively small size to prevent bubbles of air from passing the liquid therein, and which extends upwardly any desired distance, and connects with the upper portion of a vacuum chamber 16, which is supplied with a vacuum by means of a pipe 17 having a restricted opening 18, and connecting with the intake manifold of an internal combustion engine. The upper portion of the vacuum chamber 16 is also connected to the pressure equalizing pipe 12. In said chamber 16, there is a float 18 pivoted to a lever 19 pivotally supported upon a diaphragm 20, and pivotally connected to a valve 21 which closes an outlet passageway 22 when the level of the liquid in the vacuum chamber 16 is sufficiently low. The passageway 22 discharges into an auxiliary supply chamber 23 having an outlet pipe 24 leading to a carburetor of any desired type connected to the internal combustion engine, above referred to. Leading into the upper portion of the auxiliary supply chamber 22, there is also a vent pipe 25 which communicates with the outer air passing through the vacuum chamber 16.

In the form of my invention shown in Fig. 2 the construction is the same as shown in Fig. 1 except in the following respects. In this instance there is a main fuel supply tank 23 having a vented filling cap 24. Within said tank there is a check valve outlet 25 communicating with a charging chamber 25^a having connected thereto a pressure equalizing pipe 26 provided with a restricted opening 27 at the upper end communicating with a vacuum chamber 28. Said check valved outlet 25 leads by means

of another check valve 28^a to a vented measuring receptacle 29 located within the tank 23 and connected by a liquid feeding pipe 30 to said vacuum chamber 28. The 5 venting of this receptacle is secured by means of a vent pipe 31 extending above the level of the liquid in the tank 23. A vacuum is supplied to a vacuum chamber 28 by means of a pipe 32 leading to the engine manifold. The liquid which passes into the vacuum chamber 28 from the pipe 30 is discharged therefrom through a gravity closing valve 33 into an auxiliary supply tank 34, vented to the atmosphere 10 through holes 34^a, which has a float 35 located on a guide 36 arranged so that the rise of the float will open the valve 33. The auxiliary supply tank 34 discharges into the carburetor of the engine by means of a 15 pipe 37.

In the operation of my invention, referring first to Fig. 1, a quantity of gasoline or any other desired fuel having been introduced into the main fuel supply tank 1, and 20 a portion of the gasoline having been conveyed therefrom into the lower portion of the pipe 15, so as to prime the same, and the internal combustion engine having been started, so as to supply a vacuum through 25 the pipe 17 to the vacuum chamber 16, and thence by the pipe 12 to the float chamber 5, the vacuum will hold the flap valve 11 closed, and the valve 7 will be closed owing to the accumulation of the fuel in the float chamber 5. In this position of the apparatus, the 30 valve 21 also will be closed owing to the low position of the float 18^a. Thereupon, the vacuum in the vacuum chamber 16 will draw the quantity of fuel in the lower portion of 35 the pipe 15 and the measuring chamber 14 upwardly through the pipe 15, and into the vacuum chamber 16, the same being permitted by the presence of the vent pipe 13. The fuel thus conducted to the chamber 16 40 will flow into the auxiliary supply chamber 23 when the valve 21 has been opened by the rise of the level of the fuel in the chamber 16 to a sufficient extent, and thence to the carburetor of the engine, the flow out of the 45 chamber 23 being permitted by the presence of the vent pipe 25. As soon as the valve 21 has been opened in this way the vacuum in the chamber 16 will be broken by the entry 50 of air through the vent pipe 25 and as a consequence the vacuum in the pipe 12 and chamber 5 will be broken at the same time. This causes the valve 11 to open and permit a further measured quantity of liquid 55 to flow from the chamber 5 into the chamber 14. By this time all of the liquid contained in the chamber 16 will have passed through the valve 21 into the chamber 23 so as to again close the valve 21 owing to the low 60 level of the float 18^a. Thereupon the quantity of liquid in the pipe 15 and chamber 65

14 will be raised in the same manner as described previously. This cycle of operations will be continued indefinitely as long as the chamber 23 is sufficiently empty to permit the flow of fuel from the chamber 16 into the 70 same. In other words, when the fuel is being consumed there will be a continual flow out of the chamber 23 into the carburetor and the lifting of successive quantities of fuel from the chamber 14 will continue, but 75 when the chamber 23 does not need a further supply of fuel the liquid will remain at a high level in the chamber 23 and in the chamber 16 and the vacuum will remain broken in the chamber 16 by the passage of 80 air drawn from the vent 25 through the chamber 23 and into the chamber 16. The apparatus will thus continue to convey the fuel to any desired elevation, but will cease 85 operating when the supply of fuel at the delivery end has accumulated to the desired extent, and will then begin to operate again as soon as a further supply of the fuel is needed at the delivery end of the apparatus. The liquid can be raised to any desired 90 height, inasmuch as at any given time there can only be one comparatively small body of liquid rising in the pipe 15.

The form of my invention shown in Fig. 2 operates in the same manner as the apparatus shown in Fig. 1 except as set forth hereinafter. When the float 35 is in its lower position the valve 33 will be closed and a vacuum will be supplied from the vacuum chamber 28 to the pipe 26 through the 95 restricted opening 27 and simultaneously a vacuum will be supplied also in the pipe 30 to the measuring receptacle 29. As a result, the fuel will rise in the pipe 26 to a considerable extent but not to such an extent as 100 to reach the restricted opening 27 as ordinarily the vacuum will not be sufficient to elevate the fuel this far and even if the vacuum were sufficient to secure this elevation, the liquid would not reach the opening 105 27 as the small size of the same and the great head of the liquid in the pipe 26 would not permit the liquid in the pipe 26 to rise as fast as the body of liquid which has been drawn into the pipe 30 by the vacuum 110 through the check valve 28^a. It will be understood that during the application of the vacuum, owing to the presence of the vent pipe 31 the check valve 28^a is seated and only the body of liquid in the measuring 115 receptacle 29 to the rear of the check valve 28^a rises through the pipe 30. For this reason the head of the liquid at any one time in the pipe 30 is very much less than the head of the liquid column in the 120 pipe 26. When the body of liquid rising in the pipe 30 has been discharged into the vacuum chamber 28 the vacuum will be broken in the system through the vent pipe 125 31 and as a consequence the liquid in the 130

5 pipe 26 will flow into the measuring receptacle 29 from the charging chamber 25^a to again charge the same and the liquid in the chamber 28 will flow through the valve 33 into the chamber 34. After this the cycle of operations will be repeated until the level in the chamber 34 rises sufficiently to cause the float 35 to open the valve 33 and thus keep the vacuum broken until such time as 10 the level of the liquid in the chamber 34 again falls to a lower level.

10 While I have described my invention above in detail, I wish it to be understood that many changes may be made therein 15 without departing from the spirit thereof.

I claim:

1. In combination, a main supply tank, a charging chamber adapted to control the supply therefrom, a measuring chamber, 20 a vacuum chamber located at a higher level than the measuring chamber, and a pipe for conveying liquid from the measuring chamber to the vacuum chamber.

2. In combination, a main supply tank, a 25 charging chamber adapted to control the supply therefrom, a measuring chamber, a vacuum chamber located at a higher level than the measuring chamber, a pipe for conveying liquid from the measuring chamber to the vacuum chamber, and an equalizing pipe connecting the vacuum chamber and charging chamber.

3. In combination, a measuring chamber, a vacuum chamber located at a higher level 35 than the measuring chamber, a pipe for conveying liquid from the measuring chamber to the vacuum chamber, and an auxiliary supply chamber one of said chambers having a float operated valve controlling communication of the auxiliary chamber with the vacuum chamber.

4. In combination, a main supply tank, a charging chamber adapted to control the supply therefrom, a measuring chamber, 45 a vacuum chamber located at a higher level than the measuring chamber, a pipe for conveying liquid from the measuring chamber to the vacuum chamber, and an auxiliary supply chamber one of said chambers having a float operated valve controlling communication of the auxiliary chamber with the vacuum chamber.

5. In combination, a main supply tank, a charging chamber adapted to control the supply therefrom, a measuring chamber, 55 a vacuum chamber located at a higher level than the measuring chamber, a pipe for conveying liquid from the measuring chamber to the vacuum chamber, an equalizing pipe connecting the vacuum chamber and charging chamber, and an auxiliary supply chamber one of said chambers having a float operated valve controlling communication of the auxiliary chamber with the vacuum chamber.

6. In combination, a measuring chamber vented to the atmosphere, a vacuum chamber located at a higher level than the measuring chamber, and a pipe for conveying liquid from the measuring chamber to the 70 vacuum chamber.

7. In combination, a main supply tank, a charging chamber adapted to control the supply therefrom, a vented measuring chamber, a vacuum chamber located at a higher 75 level than the measuring chamber, and a pipe for conveying liquid from the measuring chamber to the vacuum chamber.

8. In combination, a main supply tank, a charging chamber adapted to control the 80 supply therefrom, a vented measuring chamber, a vacuum chamber located at a higher level than the measuring chamber, a pipe for conveying liquid from the measuring chamber to the vacuum chamber, and an 85 equalizing pipe connecting the vacuum chamber and charging chamber.

9. In combination, a vented measuring chamber, a vacuum chamber located at a higher level than the measuring chamber, a 90 pipe for conveying liquid from the measuring chamber to the vacuum chamber, and an auxiliary supply chamber one of said chambers having a float operated valve controlling communication of the auxiliary supply 95 chamber with the vacuum chamber.

10. In combination, a main supply tank, a charging chamber adapted to control the supply therefrom, a vented measuring chamber, a vacuum chamber located at a higher 100 level than the measuring chamber, a pipe for conveying liquid from the measuring chamber to the vacuum chamber, and an auxiliary supply chamber one of said chambers having a float operated valve control- 105 ling communication of the auxiliary supply chamber with the vacuum chamber.

11. In combination, a main supply tank, a charging chamber adapted to control the supply therefrom, a vented measuring chamber, a vacuum chamber located at a higher 110 level than the measuring chamber, a pipe for conveying liquid from the measuring chamber to the vacuum chamber, an equalizing pipe connecting the vacuum chamber 115 and charging chamber, and an auxiliary supply chamber one of said chambers having a float operated valve controlling communication of the auxiliary supply chamber with the vacuum chamber.

12. In combination, a main supply tank, a charging chamber adapted to control the supply therefrom, a measuring chamber, a vacuum chamber located at a higher level than the measuring chamber, a pipe for conveying liquid from the measuring chamber to the vacuum chamber, an equalizing pipe connecting the vacuum chamber and charging chamber, and a vented auxiliary supply chamber one of said chambers having a float 120

operated valve controlling communication of the auxiliary supply chamber with the vacuum chamber.

13. In combination, a main supply tank, 5 a charging chamber adapted to control the supply therefrom, a vented measuring chamber, a vacuum chamber located at a higher level than the measuring chamber, a pipe for conveying liquid from the measuring 10 chamber to the vacuum chamber, an equalizing pipe connecting the vacuum chamber and charging chamber, and a vented auxiliary supply chamber one of said chambers having a float operated valve controlling 15 communication of the auxiliary supply chamber with the vacuum chamber.

14. In combination, a liquid segregating chamber, a chamber at a higher level adapted to have a differential pressure compared 20 therewith, a passageway for conveying liquid from the segregating chamber to the higher level chamber and means for supplying a new body of liquid to the segregating chamber only when the liquid previously 25 therein has been conveyed into said higher level chamber.

15. In combination, a liquid segregating chamber, a chamber at a higher level adapted to have a differential pressure compared 30 therewith, a passageway for conveying liquid from the segregating chamber to the higher level chamber and means for supplying a new body of liquid to the segregating chamber only when the liquid previously 35 therein has been conveyed into said higher

level chamber comprising a valved charging chamber connected by a pressure equalizing pipe to said higher level chamber.

16. In combination, a liquid segregating chamber, a chamber at a higher level adapted to have a differential pressure compared therewith, a passageway for conveying liquid from the segregating chamber to the higher level chamber, means for supplying a new body of liquid to the segregating 45 chamber only when the liquid previously therein has been conveyed into said higher level chamber and a vented auxiliary supply chamber adapted to receive liquid discharged from said higher level chamber. 50

17. In combination, a liquid segregating chamber, a chamber at a higher level adapted to have a differential pressure compared therewith, a passageway for conveying liquid from the segregating chamber to the higher level chamber, means for supplying a new body of liquid to the segregating chamber only when the liquid previously therein has been conveyed into said higher level chamber comprising a valved charging 55 chamber connected by a pressure equalizing pipe to said higher level chamber and a vented auxiliary supply chamber adapted to receive liquid discharged from said higher level chamber. 60

In testimony that I claim the foregoing, I have hereunto set my hand this 26th day of April, 1920.

EDWARD A. ROCKWELL.
